UNITED STATES PATENT OFFICE.

WILLIAM S. HADAWAY, JR., OF NEW ROCHELLE, AND EDWIN N. LIGHTFOOT AND JOSEF AMON, OF NEW YORK, N. Y., ASSIGNEES TO THE CUTLER-HAMMER MFG. CO., OF MILWAUKEE, WISCONSIN, A CORPORATION OF WISCONSIN.

ELECTRICAL PLUG-CONNECTOR.

1,238,287.

Specification of Letters Patent. Patented Aug. 28, 1917.

Application filed February 24, 1913. Serial No. 750,076.

To all whom it may concern:

Be it known that we, WILLIAM S. HADAWAY, Jr., and EDWIN N. LIGHTFOOT, citizens of the United States, and residents, respectively, of New Rochelle, in the county of Westchester, and of New York, in the county of New York, both in the State of New York, and JOSEF AMON, a subject of the Emperor of Austria, residing at New York, in the county and State of New York, have invented new and useful Improvements in Electrical Plug-Connectors, of which the following is a full, clear, concise, and exact description, reference being had to the accompanying drawing, forming a part of this specification.

Our invention relates to electric plug connectors or separable connectors.

Separable connectors are used in various relations, especially in conjunction with electric devices which are not designed to be permanently mounted or connected but which are connected to or disconnected from the source of supply at will. These connectors may be used between sections of a flexible cord connector, between flexible conductors and the electric apparatus to be supplied, as for example, electric heaters of various types and between flexible conductors and the supply line.

One of the objects of our invention is to provide an improved socket which is electrically and mechanically complete in itself and which is adapted to receive a co-operating plug.

Another object is to provide an improved separable connector, the socket member of which is made up of any desired number of such independent and complete sockets assembled compactly within a suitable casting.

Another object is to provide a separable plug connector of rugged construction and compact form.

A further object is to provide a connector especially adapted to withstand high temperatures.

An additional object is to provide a connector having the advantages above enumerated, which may be economically manufactured and in which there are few parts to get out of order.

Preferred forms of connectors are illus-

trated in the accompanying drawings in which—

55

Figure 1 is a sectional view of the several parts which comprise one form of socket, showing the method of assembling the same.

Fig. 2 is a sectional view of these parts assembled.

60

Fig. 3 is a view of the detached parts of another or smaller form of single socket, some parts being shown in elevation and some in section.

Fig. 4 is an elevation of the assembled parts.

65

Fig. 5 is a further sectional elevation of one of said parts.

Fig. 6 is an elevation of another of said parts.

70

Fig. 7 is a sectional elevation of a single pole connector, the socket being of the larger size shown in Fig. 2.

Fig. 8 is a section thereof taken on the line 8—8 of Fig. 7.

75

Fig. 9 is a sectional elevation of the socket member of a two-pole connector.

Fig. 10 is a bottom plan view thereof.

Fig. 11 is a sectional elevation of the socket member of a two-pole connector having the smaller sockets shown in Fig. 4.

80

Fig. 12 is a bottom plan view thereof.

Fig. 13 is a top plan view of the plug member of a two-pole connector.

85

Fig. 14 is a sectional elevation thereof.

Fig. 15 is a sectional elevation of the socket member of a three-pole connector having the small sockets.

90

Fig. 16 is a bottom plan view thereof.

Figs. 17 and 18 are a plan view and an elevation respectively of a spring used in the socket member of the two-pole connector shown in Figs. 11 and 12.

95

Figs. 19 and 20 are similar views of the spring used in the three-pole connector.

Fig. 21 is an elevation partly in section of the plug member of a three-pole connector.

100

Fig. 22 is a sectional view of the socket member of a three-pole connector.

Fig. 23 is an end view of the three-pole socket member shown in Fig. 22 with the plugs shown in section in their respective sockets, which latter are sprung somewhat apart.

105

Fig. 24 is a similar view but with the

plugs withdrawn, whereby the sockets are in normal position, somewhat closer together.

Fig. 25 is a plan view of the socket member of a four-pole connector.

5 Fig. 26 is a similar view of said four-pole socket member with the plugs shown in section in their respective sockets, the latter being sprung apart by said plugs.

Fig. 27 is a sectional elevation of a four-pole connector plug having a casing of modified construction.

Fig. 28 is a sectional elevation of the socket member corresponding thereto.

15 Fig. 29 is an end view of said socket member.

Fig. 30 is a plan view of a four-pole wall receptacle.

Fig. 31 is a sectional elevation thereof.

Fig. 32 is an elevation of a four-pole separable connector, the plug and socket members of which are similar in outline.

25 Each connector comprises a pair of separable members which may be called the plug member and the socket member. The socket member is composed of one or more sockets, preferably in the form of spools or barrels, equal in number to the poles of the connector.

Each spool, barrel or socket is a complete 30 unitary structure. It is mechanically and electrically complete in itself. We have illustrated two different types of spool, which we shall designate, for convenience, the large socket and the small socket, the 35 question being one of relative dimensions however, rather than absolute size. The large size, that is, the one having the greatest diameter in proportion to its length, is illustrated in Figs. 1 and 2, and is composed 40 in the preferred form, of a central contact tube 1 carried concentrically in a sleeve 2 from which it is insulated. The tube 1 is open at one end to receive the plug or contact pin of the plug member and is slightly 45 larger in diameter than the pin which it is to engage. The other end of the tube has its walls bent outward and back, forming a flange 3 and has an extended portion of the walls beyond the flange pressed together as, 50 at 4 to provide a terminal. A binding screw 5 fits an opening in the terminal to support 55 and secure an electrical conductor; the corners adjacent the head of the screw being bent up to aid in securing said conductor.

55 The sleeve 2 may be formed of several parts as shown in detail in Fig. 1. The ends 6 of the sleeve are flared outward to a larger diameter to receive insulating washers 7. These washers are preferably 60 composed of mica, although fiber or other insulating material may be used. The washers fit snugly within the flared ends of the sleeve and the central openings of the washers closely embrace the ends of the tube 1.

65 When the sleeve is made in several sections,

as illustrated in Fig. 1, a central section 8 is provided which closely fits the ends 9 of the end members 6. A projection 10 on the sleeve 8 aids in positioning the spool as hereinafter described. It is understood, of course, that the sleeve might be in a single piece and provided with the flared portions 6 within which the washers are fitted.

70 In the assembled spool, as illustrated in Fig. 2, the tube is held within the sleeve by the washers 7 and the open end of the tube is formed over as at 11 to compress the insulating washers and hold the various parts in one compact unit. Metallic washers 12 and 13 may be employed to take the pressure of forming over the tube and to distribute the pressure over the insulating washers. Additional insulating washers 14 may be added on the open end of each unit to prevent the plug pin slipping between the 85 tube and sleeve. The flared portion 6 is bent inwardly as at 15 to hold the washers 14 in place. The open space 16 between the tube and the central portion of the sleeve is ordinarily sufficient to supply the necessary 90 insulation at this point, although insulating material may be introduced, if desired.

95 It will thus be seen that each barrel, spool or socket is complete in itself. The inner tube is thoroughly insulated from the outer casing so that it is immaterial whether or not said outer casing happens to be in contact with metal or insulation. After a conductor has been connected to said inner tube, said spool or socket becomes in itself the 100 socket member of a single pole separable connector. Said sockets or spools may be manufactured and kept in stock in large quantities and then readily assembled to form a separable connector of any desired 105 number of poles by simply mounting or supporting said spools or sockets in a suitable inclosing casing without regard to whether said spools are insulated from each other or from said casing, which latter may 110 be of metal or any other suitable material, either conducting or non-conducting. For example, in Fig. 7, such a spool is mounted as part of a single pole connector. In Figs. 22, 23 and 24, said spools are assembled 115 within a casing to form a part of a three-pole connector. In Figs. 25 and 26 they are arranged to form part of a four-pole connector. They are also shown mounted in various ways in other figures of the drawings, all of which are hereinafter described 120 more fully.

The smaller spool illustrated in Figs. 3 and 4, comprises in the preferred form, a central tube 17 flattened at one end and 125 having a screw threaded opening which receives a terminal screw 18, said tube being surrounded by a cylinder 19 of rolled up sheet mica, the latter having a metallic casing 20 slipped over the same and held there- 130

to by swaging in or indenting certain portions 21, thereof. Said casing is also provided with a pair of projecting lugs 22, which are preferably struck up from the metal. The assembled spool as shown in Fig. 4 is very compact, the outer casing being separated from the inner tube only by a few thicknesses of mica. The outer casing is thoroughly insulated from the inner tube however, and accordingly a number of spools may be grouped together in contact with each other, while at the same time the inner tubes 17 will be entirely independent of each other electrically. Furthermore, a number of sockets so grouped together occupy a minimum space transversely because of their relatively small diameters as compared to their lengths. Socket members made up of groups of these small size spools are shown in Figs. 11 and 15 which are hereinafter described.

In Fig. 7 a single pole separable connector is shown, consisting of a socket member 23 and a plug member 24 therefor. The socket member includes a single spool of the larger size such as shown in Figs. 1 and 2, the same reference characters being used to designate the parts thereof as have previously been employed. Said spool is mounted within a metallic casing 25, one end of which is flanged over as at 26 to hold the spool in place. The other end of the spool is secured by abutting against an inner metallic casing 27, secured to said outer casing by a screw 28, whereby it may be detached therefrom. An inner lining 29 of insulation is provided in view of the fact that the terminal conductor enters this chamber and is connected to the screw 5 in a manner that is well understood. The inner casing 27 is provided with an insulating bushing 30 in an opening in its outer end, said insulating bushing serving also to secure the insulating lining in place. The spool, although positively locked against longitudinal displacement, is loosely mounted within the casing 25 and may be shifted laterally. It is held in normal position however, slightly off center, by a spiral spring 31.

The plug member 24 comprises a metallic casing or cup 32 having a flaring end adapted to act as a guide when the socket and plug members are being assembled. Said casing has an opening in the end thereof within which is mounted the terminal pin 33, said pin being supported by said casing but insulated therefrom by a plurality of insulating washers 34, preferably made of mica. Said mica washers are clamped in position by a metallic eyelet 35, said eyelet receiving snugly a screw-threaded extension 36 on the terminal pin. A nut 37 holds the terminal pin firmly in position and may be used also to assist in securing a conductor thereto, either directly or indirectly. The

terminal pin is thus securely mounted on the casing 32, but is insulated therefrom and is preferably arranged centrally thereof. As previously stated, however, the socket or spool in the socket member, is not arranged exactly central with respect to its casing. Consequently, it is normally slightly out of alignment with respect to said pin, the interfitting casings determining the relative arrangement of the pin and socket in this regard. Accordingly, when the plug and socket members are forced together, the movable socket is sprung slightly laterally, whereupon it is held in firm frictional engagement, and hence in good electrical contact with said pin, or at least a portion of the cylindrical surface thereof.

In Figs. 9 and 10 we have illustrated a two-pole connector, the socket member of which comprises a drawn metal casing 38 within which two spools 39 are mounted, each of which is constructed preferably in accordance with the disclosure in Figs. 1 and 2. Said spools are loosely held together by an S-shaped spring 40 having a notch 41 therein. A suitable screw or rivet 42 passes through the casing from side to side, as shown in Fig. 10, and being received within said notch, prevents the spring and hence the spools, from falling out of the casing. The spring also has openings 43 therein which receive the projections 10 and prevent turning of the spools. The inner chamber of the casing is provided preferably with an insulating lining 44, as the circuit conductors 45 enter this casing and are attached to the terminal screws 5. It should be noted that there is sufficient clearance between the spools 39 and the adjacent walls of the casing to permit said spools to be sprung apart when the terminal pins are inserted therein, the axes of said spools being normally out of alignment with the axes of the terminal pins.

In Figs. 11 and 12 we have illustrated a two-pole separable connector of modified construction, the smaller spools being employed. Two spools or sockets such as shown in 4, are mounted within a suitable metallic casing 46 having an opening in one end within which a helical spring 47 is located, said spring serving as a mechanical reinforcement and protector for the conductors (not shown) which enter through said opening and are secured at their ends to the terminal screws 18. Within the outer end of said casing a metallic sleeve 48 is secured, preferably by a screw 49, said sleeve having an opening 50 in one end through which the two spools pass loosely. The outer end of said sleeve is closed by an insulating disk 51, which is held in place between a shoulder and the inwardly turned edge of said sleeve, as clearly shown in the drawing. Said insulating disk 51 is provided

with a pair of openings 52 through which the plugs or pins of the plug member are adapted to pass. The inner ends of said openings are enlarged as at 53, to receive 5 loosely the outer ends of the spools or sockets. Each socket is accordingly locked against end-wise displacement, but may have suitable lateral movement. Said sockets are normally yieldingly impelled toward 10 each other by a spring 54, shown more clearly in Figs. 17 and 18. Said spring is provided with a pair of notches 55 within each of which one of the lugs 22 fits loosely, to prevent turning of the spools. Said 15 springs are thereby properly positioned with respect to said spools and, while loosely secured thereto, nevertheless they cannot be accidentally detached therefrom, nor can the spools get out of proper position. The 20 spring yieldingly holds said spools in a certain normal position, but permits said spools to be sprung apart somewhat, when the contact pins on the plug member are inserted therein.

25 One form of plug member is illustrated in Figs. 13 and 14, and consists of a metallic casing 56 having a pair of terminal plugs or pins 57 mounted in an opening in the end thereof and suitably positioned therein 30 and insulated therefrom by mica washers in a manner similar to that previously described. Said pins are normally spaced apart a distance slightly greater than the normal distance between the axes of the two 35 coöperating spools whereby said spools are forced apart by said pins and caused to have firm frictional engagement therewith. In the present instance it will be seen that when the terminal pins are being inserted in the 40 sockets, either pin may be assumed to be normally in alignment with the coöperating socket, whereupon the elements of the other pair, namely the other pin and socket, will be normally out of alignment or off-set, as 45 compared to the elements of the first pair.

In Figs. 15 and 16 we have illustrated a three-pole connector in which the smaller spools or barrels are employed. Said spools are similar to those described in connection 50 with Figs. 11 and 12, and are mounted in a similar manner, except as to certain minor changes. For example, the spring 58 shown in Figs. 19 and 20, is so shaped as to partially embrace all three spools which are 55 loosely locked thereto by their lugs 22 which fit into notches 59 in said spring, thereby preventing turning of said spools. The casing 60, in the present instance, is provided with a projecting portion 61 struck 60 therefrom to act as a guide in properly locating the pins of the plug member with respect to said socket member. Where three contacts are used, it is desirable that each 65 contact pin shall close a circuit to a particular spool and to no other. With the

projection 59 and suitable coöperating means on the plug member, the relative arrangement of the circuit connections may be accurately predetermined. Three pole connectors are frequently used in connection 70 with heating appliances where it is desirable to have available two or more heats by connecting two unequal resistors either singly or in parallel. Under these circumstances a three-pole connector may be used as a controller by varying the relative angular arrangement of the parts when they are coupled together, in a manner that is well understood.

Figs. 21 and 22 illustrate three-pole socket 80 and plug members made up of units formed as described in connection with Figs. 1 and 2. The spools are held loosely within a casing 62 by pins 63 passing through the opposite casing walls and engaging beneath the 85 flared ends 6 of the spools. The spools are yieldingly drawn together by means of springs. For this purpose S-shaped springs 64 may be employed, the curved ends of each spring embracing the sleeve 8 of a 90 spool and yieldingly drawing them together, or a single spring 65, properly shaped, may embrace all of the spools and yieldingly draw them together. In Figs. 23 and 24 95 an arrangement of springs is illustrated in which an S-shaped spring 64 is used in conjunction with a compound spring 65 to more firmly hold the spools. The bosses 10 formed on each sleeve 8 coöperate with openings in the ends of the springs to hold the units 100 in place and prevent twisting of their terminals. The springs are preferably recessed as at 66 to provide for the pins 63. A lining of insulation 67, preferably composed of mica strips, is provided within the 105 casing opposite the terminal screws 5. An insulating bushing 68 in the end of the casing, has an opening through which pass the conductors 69.

The plug member illustrated in Fig. 21 110 consists of a number of contact pins 70, equal in number to the spools in the socket member. These pins are preferably rigidly mounted in a metallic base 71 and are insulated therefrom as at 72. The base 71 is 115 provided with an insulating lining 73. Said base is mounted within a casing 74 similar to the casing 62 but arranged to telescope over the same. A suitable terminal 75 on each pin provides for attaching the conductors 76.

The pins are preferably arranged with a distance between their axes slightly greater than the normal distance between the axes of the tubes in the socket member. When 120 the pins on the plug member are pressed into the tubes on the socket member, the spools are moved laterally against the tension of the springs as illustrated in Fig. 23, causing the tubes to exert pressure against 125 130

the pins, thereby insuring a good electrical contact and sufficient mechanical friction to hold the parts firmly together.

Figs. 25 and 26 illustrate a four-pole connector. Four spools or barrels are arranged in this form in pairs with a single S-shaped spring embracing each pair and holding them yieldingly together as illustrated in Fig. 25. Upon insertion of the plug pins the 10 spools are forced apart, assuming the position illustrated in Fig. 26. It is evident, of course, that in place of S-shaped springs, a single spiral spring could be used which would embrace each of the barrels so as to 15 draw them together as desired.

Figs. 27, 28 and 29 illustrate a further form of four-pole connector, many of the elements of which are similar to elements previously described and accordingly, the 20 same reference characters have been employed. The casings are of different form and are constructed preferably of cast metal instead of drawn metal; aluminum being very desirable for this purpose. The casing 25 77 of the plug member is provided with an annular flange or rib 78 whereby it may be readily grasped by hand. The casing 79 for the socket member is also constructed preferably of aluminum. This connector may 30 be used as a three heat connector by coupling the members together in any one of several possible positions of angular rotation.

Figs. 30 and 31 illustrate a wall socket adapted to receive a four-pole connector 35 plug such as shown, for example, in Fig. 27. Said wall socket comprises a pair of face plates 80 and 81 held together by screws 82 which pass through lugs 83 on the under surface thereof. The barrels, which are 40 similar to those shown in Figs. 1 and 2, are held in place by a projecting shoulder 84 which fits into the reduced middle portion of each barrel to a certain extent and thereby locks the same in position, with the outer 45 ends thereof about flush with the outer surface of the face plate. See Fig. 31. The barrels or spools are suitably held together by springs similar to those described above, whereby they may be forced apart somewhat 50 when the plug is inserted. An inclosing casing 85 is provided, which is secured to the face plate by screws 86 which pass through ears 87 on said casing. After said casing is in place, the two halves of the face 55 plate 80, 81, cannot be separated, nor can access be had to the securing screws 82.

In Fig. 32 we have illustrated a separable attachment plug consisting of a 60 socket member 88 and a plug member 89, the internal construction of which may be the same as that illustrated in Figs. 27 and 28 or the small spools may be employed. Said outer casings are each provided with an annular flange or bead 90 to facilitate 65 separation thereof. This connector is in-

tended primarily as a three heat connector, the two members being adapted to fit into each other in any one of four different angular positions, ninety degrees apart.

Although both the large spools and the 70 small spools have various advantages which adapt them for use in particular relations, the small spool is particularly adapted for use where a plurality of such spools have to be grouped side by side, and parallel, 75 within a limited inclosure. For this reason, the smaller spools may be used advantageously within the hollow handles which are usually attached to heating appliances of various kinds. 80

The contact between the pins and tubes is theoretically a line contact owing to the difference in the circumference of the pins and tubes. This is ordinarily sufficient, but if it is desired to secure a larger contact area, 85 the pins may be so shaped as to provide a portion of their surfaces formed on an arc of the same radius as the internal diameter of the tubes.

While the spools have been described as 90 movable and the pins as rigidly mounted, it will be apparent that this arrangement may be reversed or that both pins and spools may be spring-held in position, if desired. It is also apparent that all of the 95 pins need not be mounted on one member nor all of the sockets on the other member, as part of the pins and part of the sockets may be arranged each on one member. This is particularly advantageous in connection 100 with a two-pole connector where it is desired to maintain the proper polarity of a circuit. Accordingly, we do not limit ourselves to an arrangement wherein all of the 105 plugs are mounted in one group and all of the sockets in another group. In general, we do not desire to limit ourselves to the particular forms of the invention described and illustrated, nor to the details, thereof, except where limitations appear in the appended claims. On the contrary, we desire 110 to cover broadly suitable equivalent means for accomplishing the desired results wherever said means fall within the scope of the appended claims. 115

What we claim as new and desire to secure by Letters Patent is:

1. A connector comprising a casing, a plurality of electrically and mechanically complete sockets therein, a spring for normally biasing said sockets toward one another, said spring and sockets having co-operating notches and projections by means of which said sockets are prevented from rotating. 120

2. A connector having a plug member provided with a plurality of plug contacts, a socket member comprising a casing having a plurality of mechanically and electrically complete sockets therein and a spring for 130

normally biasing the socket members out of alignment with the plug members, said spring having notches therein coöperating with projections on the sockets to prevent 5 rotation of said sockets.

3. A connector having a plug member provided with a plurality of plug contacts, a socket member comprising a casing having a plurality of metal-incased mechanically and 10 electrically complete sockets therein, and a spring for normally biasing the socket members out of alignment with the plug members, said spring having notches therein coöperating with projections struck up from 15 the casings of said sockets to prevent rotation of said sockets.

4. A connector having a plug member provided with a plurality of plug contacts, a socket member comprising a casing having 20 a plurality of mechanically and electrically complete sockets therein, and yielding means for normally biasing the socket members bodily out of alignment with the plug contacts whereby when said members are 25 brought into engagement the sockets exert a pressure on the plugs to secure good electrical contact.

5. A connector having a casing, a plurality of mechanically and electrically complete 30 sockets in said casing, each socket comprising an inner conducting portion and an outer supporting portion insulated therefrom and each of said sockets being mounted to allow bodily lateral movement thereof 35 and a plug member having a plurality of plug contacts coöperating with said sockets.

6. A connector comprising a casing, a plurality of electrically and mechanically complete 40 sockets loosely mounted in said casing, an insulating base in one end of said casing having openings therein through which the plug contacts of a plug member may be inserted and yielding means for normally biasing the sockets bodily out of alignment 45 with the openings in the base.

7. A connector comprising a casing, a plurality of mechanically and electrically complete 50 sockets therein, each of said sockets comprising an inner conducting portion and an outer supporting portion insulated therefrom and each of said sockets being adapted to be mounted in the casing without being disassembled and each socket carrying its own electrical terminal.

8. A socket member for a connector comprising a casing having a plurality of sockets 55 therein, each of said sockets being mechanically and electrically complete in itself and comprising an inner conducting portion and an outer supporting portion insulated therefrom whereby it may be mounted in said casing without being disassembled and without being insulated from said casing, said sockets being mounted to allow lateral movement thereof in the casing so that

the sockets may adjust themselves to the plug contacts of the plug member of the connector.

9. A connector comprising a casing having a plurality of electrically and mechanically complete 70 sockets therein each of said sockets comprising an inner conducting portion and an outer supporting portion insulated therefrom and each of said sockets carrying its own electrical terminal and being mounted to allow lateral movement so that the sockets may adjust themselves to the plug contacts of a plug member.

10. A connector comprising a casing and a plurality of electrically and mechanically complete 75 sockets loosely mounted therein so that the sockets may move relatively to themselves and to the casing to adjust themselves to the plug contacts of a coöperating plug member, each of said sockets comprising 80 an inner conducting portion and an outer supporting portion insulated therefrom.

11. In a connector, a plug member provided with a plurality of contact elements, a socket member provided with a plurality of socket elements coöperating with said contact elements, a casing inclosing the elements of one of said members, and yielding means drawing said elements together in 90 said casing, said elements being independently movable against the action of said yielding means, whereby they may adjust themselves to the positions of the corresponding elements of the other member. 100

12. In a connector, a plug provided with a plurality of plug contacts, a socket member provided with a plurality of sockets adapted to coöperate with the plug contacts, and yielding means for biasing the sockets 105 toward each other whereby they are normally out of alignment with the plug contacts, and whereby when the plug contacts and sockets are brought into engagement the sockets exert pressure on the plug contacts. 110

13. In a connector, a casing, a plurality of electrically and mechanically complete 115 sockets in said casing, each of said sockets comprising an inner conducting portion and an outer supporting portion insulated therefrom, and means for biasing said sockets toward one other.

14. A socket member for a connector, comprising a casing, a plurality of electrically complete 120 sockets yieldably mounted in said casing, and a spring for normally biasing the sockets toward each other.

15. A connector having a plug provided with a plurality of plug contacts, a socket member comprising a casing, a plurality of 125 electrically and mechanically complete sockets in said casing, each of said sockets comprising an inner conducting portion and an outer supporting portion insulated therefrom, and means for biasing said sockets to- 130

ward each other whereby they are normally held out of alinement with the plug contacts.

16. A socket for a plug connector comprising an inner contact tube flattened at one end and having an opening in said flattened end to receive a terminal screw, a thin insulating tube closely embracing said inner tube, and an outer metallic casing encircling said insulating tube and having 10 bent in portions forced into said insulating tube to insure firm engagement between all three concentric elements.

17. In a socket for a plug connector, an inner contact tube, an outer supporting tube, 15 insulation between said tubes holding one to the other, said outer tube having means thereon to aid in positioning the socket within a suitable casing.

18. In a socket for a plug connector, an inner contact tube, an outer supporting tube, insulation between said tubes holding one to the other, said outer tube having means thereon to aid in positioning the socket within a suitable casing, said means comprising tongues struck up from said outer tube and projecting therefrom.

19. In a socket for a plug connector, a contact tube having one end flattened to provide for a terminal connection, a thin

tube of insulating material closely surrounding said contact tube, the other end of the latter being flared outwardly, and a metallic jacket closely surrounding said insulating tube over part of its length, said jacket being swaged in against said insulating tube 30 to increase the frictional engagement of the parts and radially projecting tongues on said jacket for locating said socket and preventing twisting thereof.

20. A connector comprising a casing, a 40 plurality of sockets therein, each socket comprising an inner conducting portion and an outer supporting portion insulated therefrom, and a spring for normally biasing 45 said sockets toward one another, said spring and sockets having coöperating notches and projections by means of which said sockets are prevented from rotating.

In witness whereof, we have hereunto subscribed our names in the presence of two 50 witnesses.

WILLIAM S. HADAWAY, JR.

EDWIN N. LIGHTFOOT.

JOSEF AMON.
